Alex. P. Browne

UNITED STATES PATENT OFFICE.

ALEXANDER P. BROWNE, OF BOSTON, MASSACHUSETTS; ASSIGNOR TO THE WEEDEN SANITARY MANUFACTURING COMPANY, OF RHODE ISLAND.

AUTOMATIC FLUSHING DEVICE.

SPECIFICATION forming part of Letters Patent No. 416,091, dated November 26, 1889.

Application filed June 19, 1889. Serial No. 314,816. (No model.)

To all whom it may concern:

Be it known that I, ALEXANDER P. BROWNE, of Boston, in the county of Suffolk and State of Massachusetts, a citizen of the United States, have invented certain new and useful Improvements in Automatic Flushing Devices, of which the following is a specification.

My invention relates to that class of apparatus in which the flushing of the bowl of a urinal or similar structure is accomplished by means of siphon action produced by the downward and outward passage through a pipe of suitable caliber of liquid introduced from without into the bowl.

Heretofore several forms of these devices have been constructed in which the overflow through a pipe of suitable caliber of liquid poured into the bowl produced a rarefaction of the air in the long leg of a siphon-formed flushing-pipe, the short leg of which communicated with a tank or other suitable water-supply. According to my present improvement, although I still employ the principle of siphonage brought about by the discharge from the bowl of its liquid contents, yet I do not avail of this siphonage to start the flushing action directly, but through the intervention of a floatable valve, as will herein-after appear.

In the accompanying drawings I have represented in elevation and section at Figure 1 a device embodying my present invention in a convenient form, and at Fig. 2 an illustration of a simplified form thereof.

In the drawings, A represents the bowl to be flushed; B, the flushing-pipe leading thereto, and C the tank or water supply. Below the bowl I provide an outlet or waste pipe D, of suitable caliber, through which liquid poured into the bowl from without may pass out. This pipe is provided with a back-air cut-off d, and an overflow or surplus waste-pipe E may also be provided, as shown. The function of the back-air cut-off is, as is well known, to prevent air passing into the pipe D to supply the place of that driven out by the flow of liquid through the pipe.

In connection with the pipe D, and at a point on the sewer side of the back-air cut-off, I provide an air-pipe F, extending upwardly and terminating in a siphon within

the tank. The end of this siphon is within a floatable cup G, the bottom of which is formed as a valve, which rests upon and normally closes a water-way into the flushing-pipe B. 55 This flushing-pipe may also itself be provided at its upper end with a siphon, (shown at H,) although, as will be hereinafter pointed out, this last feature is not essential.

In order to regulate the discharge of water 60 in the operation of the apparatus, the cup-valve G, with its water-way and the flushing-siphon H, may be inclosed within chambers partitioned, as shown, from the main body of the tank, but connecting therewith by small 65 orifices g h, as shown, this feature of construction being common and well known for the purpose.

I will now describe the operation of the apparatus: Assuming the tank C to be filled 70 with water to its normal level—as, for example, a a—it is obvious that the cup-valve G will be filled with water and will rest upon and close the water-way into the flushing-valve B. If now liquid be poured into the 75 bowl A and descend through the pipe D, it will expel the air therefrom, thus rarefying the air in the pipe F. This will produce siphonic action in that pipe, which will first lower the water-level in the chamber surrounding 80 the cup-valve G down to the level of the cup, and then continuing will empty the cup of its liquid contents sufficiently to cause it to float up and open the water-way into the flushing-pipe B, thereby allowing flushing-water to descend through that pipe to the bowl until such 85 descent of the water lowers the cup-valve G back to its original position and closes the water-way.

The essential parts of the apparatus so far 90 described are represented at Fig. 2, in which b b show the level of the top of the cup, the subsequent withdrawal of water from which causes it to float upward and so open the mouth of the flushing-pipe B. If, however, 95 a longer flush be desired, it may be obtained by means of the siphon attachment H, the siphon action of which will be started by the descent of water caused by the raising of the cup-valve, and the siphon-flush thus obtained will continue until the level of the water surrounding the short leg of the siphon 100

H has fallen sufficiently to uncover its mouth, when the siphon action breaks and the flush ceases. Water is then resupplied to the tank up to its normal level, thereby restoring the 5 apparatus to its original condition.

I claim—

1. In an automatic flushing device for urinals and similar structures, the combination, with the bowl to be flushed, of a flushing- 10 pipe extending therefrom to the flushing-tank, a water-way from the flushing-pipe to the interior of the tank, a floatable cup provided with a valve adapted to rest upon and close said water-way, a waste-pipe below the bowl 15 having a back-air cut-off therein, and an air-pipe extending from the said waste-pipe on the sewer side of the said air cut-off upwardly to the cup within the tank, and formed at its upper part into a siphon having its short leg 20 within the cup, substantially as set forth.
2. In a device of the character described, the combination, with the bowl to be flushed,

of a flushing-pipe extending therefrom to the flushing-tank, a water-way from said flushing-pipe to the interior of the tank, a siphon 25 II, connected with the flushing-pipe and communicating with the water in the tank, a floatable cup provided with a valve adapted to rest upon and close said water-way, a waste-pipe below the bowl having a back-air cut- 30 off therein, and an air-pipe leading from the said waste-pipe on the sewer side of the said air cut-off upwardly to the cup within the tank and formed at its upper part into a siphon having its short leg within the cup, sub- 35 stantially as set forth.

In testimony whereof I have hereunto subscribed my name this 15th day of June, A. D. 1889.

ALEX. P. BROWNE.
